FIG. 1

FIG. 2

FIG. 3

FIG. 4

FIG. 5

FIG. 6

FIG. 7

FIGURE 1 is a top perspective view of a box for a lettering set showing our new design in closed condition;

FIGURE 2 is a front elevational view thereof;

FIGURE 3 is a top plan view thereof;

FIGURE 4 is an end elevational view thereof;

FIGURE 5 is a perspective view thereof with the box in open condition with the removable tray therein and a block having a design of apertures positioned in one compartment of the tray;

FIGURE 6 is a top plan view of the removable tray thereof on an enlarged scale with the block having a design of apertures in one compartment thereof;

FIGURE 7 is a perspective view of the tray with the block omitted.

The bottom of the box is substantially plain and unornamented except for a transversely extending rib at each end thereof as shown in FIGURES 2 and 4.

We claim:

The ornamental design for a box for a lettering set, substantially as shown and described.
